(57) **CLAIM**

The ornamental design for a water pipe as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a water pipe, showing my new design;

FIG. 2 is a rear view thereof;

FIG. 3 is a left side enlarged view thereof;

FIG. 4 is a right side enlarged view thereof;

FIG. 5 is a top view thereof;

FIG. 6 is a bottom view thereof;

FIG. 7 is a top perspective view thereof;

FIG. 8 is a pipe in bent configuration thereof;

FIG. 9 is a rear elevation enlarged stretched view thereof; and,

FIG. 10 is a front elevation enlarged stretched configuration.
